UNITED STATES PATENT OFFICE.

FRANK H. MERRILL, DECEASED, LATE OF HENNEPIN COUNTY, MINNESOTA, BY GRACE E. MERRILL, ADMINISTRATRIX, OF MINNEAPOLIS, MINNESOTA, ASSIGNOR TO VEERAC COMPANY, OF MINNEAPOLIS, MINNESOTA, A CORPORATION OF MINNESOTA.

FIRE-SCREEN FOR EXPLOSIVE-ENGINES.

1,817,931.

Specification of Letters Patent.

Patented Oct. 7, 1919.

Application filed May 14, 1917. Serial No. 168,467.

To all whom it may concern:

Be it known that FRANK H. MERRILL, deceased, late citizen of the United States, and resident of the county of Hennepin and State of Minnesota, had invented certain new and useful Improvements in Fire-Screens for Explosive-Engines; that GRACE E. MERRILL, widow of the said FRANK H. MERRILL, has been duly appointed administratrix of the estate of said FRANK H. MERRILL, and that the said GRACE E. MERRILL, administratrix, does hereby declare the following to be a full, clear, and exact description of the invention, such as will enable others skilled in the art to which it appertains to make and use the same.

This invention relates to explosive engines and provides an improved form of fire screen for preventing back-firing of the charge into the crank shaft compression chamber of an explosive engine.

Generally stated, the invention consists of the novel devices and combinations of devices hereinafter defined and described in the claim.

In the accompanying drawings, which illustrate the invention, like characters indicate like parts throughout the several views.

30 Referring to the drawings:

Figure 1 is a plan view with some parts broken away, showing the improved fire screen applied in the transfer passage of an explosive engine of the two cycle type;

35 Fig. 2 is a vertical section on the line 2—2 of Fig. 1; and

Fig. 3 is a plan view with some parts sectioned, showing the improved fire screen in detail.

40 Of the parts of the explosive engine, it is only necessary for the purpose of this case to particularly note the cylinder 4 and the crank shaft compression chamber 5 into which the inner end of the cylinder directly opens. The cylinder has a fuel admission port 6 and an exhaust port 7, and it is connected to the crank shaft compression chamber at its intermediate portion by a transfer passage 8 which at one extremity forms a chamber 9 and port 10. The chamber 9 is normally closed by a removable cover plate 11.

The improved fire screen, shown in detail in Fig. 3, is made up of a multiplicity of laterally spaced thin metal washers 12 and 55 interposed relatively small spacing washers 12^a, the entire stack being held together in cylindrical form by a clamping bolt 14 provided with a nut 15.

In some instances, the cylindrical screen 60 will be interposed directly in a seat formed in the transfer passage 8, but, as shown, it is directly seated within a cylindrical cutoff valve 16 and is mounted to oscillate in the cylindrical seat formed as a part of the 65 transfer passage 8. This cutoff valve 16 has diametrically opposite ports 17 which in one portion of the valve open the transfer passage 8, as shown in Fig. 2. The valve 16 has a shaft or stem at one end that is 70 equipped with an operating lever 18 that may be directly operated or connected to an extended operating connection, not shown.

When the valve 16 is in its open position, shown in Fig. 2, the screen will operate just 75 as if it were inserted directly into a cylindrical seat formed in the said transfer passage, and, in fact, it is then in effect so seated.

It is a well known fact that a fire screen 80 prevents flames from passing through the same, by rapid radiation of the heat which reduces the flame below the flashing point of most gases. In this improved screen the plurality of metal washers serve to rapidly 85 conduct the heat, as well as to break up the flame, and thus to prevent the flame from igniting gas that is within the crank shaft compression chamber or in the transfer port 8 between said compression chamber and 90 screen.

When the valve is in an open position, the interior thereof and the ports therein constitute an expanded chamber in the transfer port in which the fire is interposed. 95 The spacing washers being of much less diameter than the heat conducting washers, or disks, constitute a core which divides the hot gases into two streams and causes the two streams to pass between different portions of said plates. This produces the greatest possible efficiency in the fire screen with a minimum of obstruction to the passage of the gases. The two streams divided

by the core are, of course, each sub-divided into a multiplicity of streams in passing between the conducting plates.

It is also important to note that the disk-like conducting plates of the fire screen, when placed within the hollow valve have direct contact with the interior of said valve at its peripheral edges so that there will be a good conduction of heat, first, to the said valve, and from thence, to the cylinder casting.

It will be noted that when the plug 4^a is removed the fire screen, as an entirety, may be removed from the valve and may be cleaned and reinserted without disturbing or removing the valve. On the other hand, when the plug 4^b is removed, the valve, together with the fire screen therein, may be removed from the valve seat. These functions, as is obvious, are important in the operation of an engine. Where a firing screen may require frequent cleaning and where it is also desirable that when the valve is removed the plug be brought therewith out of working position.

In actual practice, the above fire screen has been found highly efficient for the purposes had in view. In fact, it has been

found much more efficient than an ordinary woven wire screen.

30

What is claimed is:

The combination with a cylinder and crank shaft compression chamber, of an explosive engine, the said cylinder and compression chamber being connected by a 35 transfer passage that includes a sleeve-like valve seat, of a hollow cylindrical valve seated in said transfer passage and having lateral ports, a fire screen detachably seated in said valve, independently removable 40 plugs closing the ends of said valve seat, said valve having an operating stem extended through one of said plugs, that end of the cavity of said valve that is adjacent to the opposite plug being open for the removal 45 of said screen from said valve, when said latter noted plug is removed.

In testimony whereof I affix my signature in the presence of two witnesses.

GRACE E. MERRILL,
Administratrix of Frank H. Merrill, deceased.
